DOOR LOCK

Henry G. Voight and William S. Edwards, Hamden, Conn., assignors to Sargent & Company, New Haven, Conn., a corporation of Connecticut

Application January 18, 1945, Serial No. 573,339

12 Claims. (Cl. 292—169)

1

This invention relates to door locks and more particularly to a lock designed to be used in connection with a front door of a building or dwelling, although it will be understood that the principles of the invention may be applied to locks for other uses and for doors employed in other locations.

In the manufacture of locks it is desirable to construct the lock so that it may be used with a door of either hand, regardless of which edge of the door may be the hinged edge. In the ordinary mortise lock this result is often achieved by so constructing the latch bolt of the lock that it may be reversed in position. However, it often occurs that in removing the latch bolt for reversal, parts of the mechanism are disturbed so that the reversal of the bolt is attended by considerable inconvenience. Also in the case of a door which employs a so-called guard bolt or auxiliary bolt controlling a latch dogging member, it is impossible to reverse the latch bolt as the hole in the strike plate is not symmetrical, the auxiliary bolt usually being received in a portion of the same opening in which the latch bolt is received.

The present invention relates to a lock of the type in which an auxiliary or guard bolt is provided to control a latch dogging member and is designed to provide a lock which may be readily and cheaply manufactured and, at the same time, will be applicable to doors which open in either direction and which may be hinged at either edge. Moreover, the lock case in the present instance is one of tubular form so that it may be readily inserted in a bore through the edge of the door and also may be made of wrought metal, thus being less expensive than the usual cast metal door locks.

As shown, the lock is provided with an auxiliary case or bolt case which may be removably mounted at the forward end of the main case; the bolt case containing the latch bolt and protracting bolt spring and also containing the guard bolt and associated parts. This auxiliary case and bolt mechanism is so constructed that it may be inserted in the main case as a unit and may be reversed in position relatively to the main case so that the beveled edge of the bolt may face in either direction. The bolt stem and the stem of the dogging member project through an opening in the auxiliary case to be engaged by a retracting member in the main case. The latter is constructed in two parts which are substantially alike, and it is only necessary to remove one of the parts or the cover of the main case and

remove the bolt case with its contained mechanism to reverse the latter and replace it in reversed position, which operation may be performed without disturbing any of the working parts of the mechanism.

One object of the invention is to provide a new and improved door lock of simple construction which may be economically manufactured.

A further object of the invention is to provide 10 a door lock having a bolt dogging mechanism of novel form controlled by a guard bolt projecting from the face of the lock beside the latch bolt, which bolt and associated structure may be readily assembled in reversed positions with respect to 15 the remaining parts of the lock.

A still further object of the invention is to provide 20 a front door lock having a main case and an auxiliary bolt case, the bolt case having therein the bolt itself and bolt dogging mechanism which extends rearwardly into the main case and which 25 engages the rear portion of the auxiliary case to dog the bolt against retraction.

Still another object of the invention is to provide 30 a tubular lock having rollbacks mounted therein in a novel and improved manner.

To these and other ends the invention relates to the novel features and combinations of parts to be hereinafter described and claimed.

In the drawings:

30 Fig. 1 is a longitudinal sectional view through the case of the lock;
Fig. 2 is a top plan view of the lock with the cover of the case removed to show the interior mechanism;
35 Fig. 3 is a view similar to Fig. 2 showing the front portion of the lock case with the parts in another position;

Fig. 4 is a sectional view on line 4—4 of Fig. 3;

Fig. 5 is a sectional view on line 5—5 of Fig. 3;

Fig. 6 constitutes front and rear end views and a side view of the guard bolt;

Fig. 7 is a perspective view of the controlling slide of the latch dogging lever;

Fig. 8 constitutes front and rear end views and a side view of the latch bolt; and

Fig. 9 is a sectional view on line 9—9 of Fig. 2.

To illustrate a preferred embodiment of my invention I have shown a lock comprising a case 40 having therein mechanism which would normally be employed in a front door lock. As will be apparent, this case is of substantially cylindrical form from front to rear so that it may be inserted in a cylindrical bore formed in the edge of the door. This case 41, which I term the main case, lock, consists of two substantially similar

sections 12 and 13, the latter having secured thereto a post 14 in which is threaded a screw 15 passing through an opening 16 in the section 12 to secure the parts together. At the rear end of section 12 is a substantially semi-circular member 17 which cooperates with a member 18 of similar shape secured to the section 13 to close the rear end of the case when the two sections are secured together.

The casing parts are provided with openings 21 and 22 for the reception of rollback hubs to be described hereinafter and also with openings 23 and 24 for the reception of a dogging member. Rearwardly of the post 14 a pair of U-shaped bearing members 25 and 26 are secured to the respective casing portions, these members having elongated flat body portions which are provided with openings 27 and 28 acting as bearings for the rollback hubs and are also provided with openings 29 and 30 for the dogging member 31.

This case is open at its forward end, and disposed in the front portion thereof when the parts are assembled is a bolt case 32 which is of cup-shaped form having a cylindrical body portion designed to fit snugly within the front open end of the main case and project slightly therefrom and a rear or bottom wall 33 provided with an opening 34. Secured to the front end of the bolt case is a face plate 35, this member being held in place by outwardly turned tongues or lugs 36 on the bolt case. To the face plate 35 may be secured the usual finishing plate 36a which is provided with an opening of non-circular shape 37 to slidably but non-rotatably receive the head 38 of the latch bolt and the head 39 of the guard bolt.

It will be apparent that the two portions 12 and 13 of the main case may be separated by removal of the screw 15 when it is desired to assemble the bolt case 32 therein and that the latter snugly fits within the bolt case and is held against movement therein by any desired means such, for example, as a pin 40 secured to the main case and two or more openings 41 are formed in the bolt case to receive the pin. Thus the bolt case may not only be adjusted longitudinally of the main case by inserting the pin 40 in a selected one of the openings 41 but may also be reversed in position or turned through an angle of 180° about its axis as may be necessary to reverse the position of the latch and guard bolts to fit a door of either hand.

Within the bolt case a bolt is reciprocably mounted which comprises the bolt head 38 and stem 43, this stem being provided with a reduced portion 44 and a crosshead 45 on its rear end. It is also provided with a longitudinal guide slot 46. The bolt is urged to protracted position by means of the spring 47 acting against the bolt at its front end and against the rear wall 33 of the bolt case at its rear end.

Adjacent the latch bolt just described is the auxiliary or guard bolt comprising the head 39 and a tail portion 48 having an annular groove 49. This guard bolt is urged to protracted position by a spring 50 surrounding a stem 51 secured in the rear wall of the bolt case and adapted to be received in a bore 52 in the guard bolt. This spring acts at its forward end against the tail of the guard bolt and at its rear end against the rear wall 33 of the bolt case.

Pivotedly secured to the bolt stem at 54 is a dogging lever 55, this dogging lever having a tail portion 56 extending rearwardly through 75

the opening 34 in the bolt case (as does also the stem 43 of the latch bolt) and a toe portion 57 disposed adjacent the rear face of the head 38 of the latch bolt. A plunger 58 mounted in the head of the latch bolt and urged rearwardly by a spring 59 acts against the toe 57 of the dogging lever to urge it about its pivot 54 in a counterclockwise direction and thus urge the tail portion 57 upwardly so as to engage the forward edge 60 of a recess 61 in the tail portion of the dogging lever with the edge of the opening 34 as shown in Figs. 2 and 3.

It may here be stated that the opening 34 in the bolt case as shown in Figs. 3 and 4, for example, is sufficiently large over the greater part of its width to permit the passage therethrough of the crosshead 45 of the bolt stem 43 but is reduced in size adjacent one edge as shown at 62 (Fig. 4) to permit the engagement therewith of the edge 60 of the recess 61 when the latter is raised by the plunger 58 as shown in Fig. 4. However, when the dogging lever 55 is in its normal position the tail portion thereof as well as the crosshead 45 will both pass freely through the opening 34.

Means are provided as is usual in this type of locks for holding the dogging lever in an inoperative or non-dogging position except when the door is closed. That is, when the door is open and both latch bolt and guard bolts are protracted as shown in Fig. 1, the dogging lever will occupy the position shown in Fig. 2 in which the stem of the latch bolt and the stem of the dogging lever will slide freely through the opening 34. When the door is closed, however, and the guard bolt is held in retracted position by the strike plate in the usual manner, the plunger 58 is permitted to swing the dogging lever about its pivot 54, thus engaging the rear end of this lever with the opening 34 and preventing the retraction of the latch bolt except by operation of the door knob as will be hereinafter explained.

For this purpose I have provided a dog controlling slide shown, for example, in Fig. 7. This slide comprises a body portion 65 having at its forward end a yoke 66 designed to be engaged in the recess 49 of the guard bolt so that this slide will be reciprocated with the guard bolt. The body portion of the slide is also provided with a guide lug 67 disposed within the guide slot 46 of the stem of the latch bolt and a pair of laterally directed wings 68 overlying the upper and rear edges of the stem portion 43 of the latch bolt. It will be noted from Fig. 2 that one of these wings normally engages the toe portion 57 of the dogging lever and holds the latter against the latch bolt in opposition to the plunger 58 and spring 59. This normally holds the rear end of the dogging lever downwardly in the position shown in Fig. 2 in which it is free to slide through the opening 34. However, when the guard bolt 39 is retracted by the strike plate as shown in Fig. 3, the wing 68 is withdrawn from engagement with the toe 57 and permits the plunger 58 to swing the dogging lever to an operative or dogging position.

Mounted in the main case of the lock is a reciprocating bolt retractor 70 in the form of a yoke having a head portion 72 provided with a laterally opening slot 73 to receive the rear ends of the bolt stem 43 and dogging lever 55. This retractor is urged in a forward direction by the spring 74 surrounding the post 75, the spring acting against the head 72 and against the post 14. The legs of the retractor member 70 extend

rearwardly and are provided with laterally projecting portions 77 adapted to be engaged by inner and outer rollbacks 78 and 79, these rollbacks being provided upon hubs 80 and 81 rotatably mounted in the lock case and designed to be rotated by inner and outer knob spindles 82 and 83.

The leg portions 70 of the retractor may also be provided with struck-up guide lugs 84 adapted to be guided in their reciprocating movement in slots 85 in the portions 12 and 13 of the case. It may also here be noted that the rollback hubs 80 and 81 are mounted in the openings 21 and 22 of the lock case and aligned openings in the bearing plates 25 and 26 and are held in position in the sections of the case by means of split rings 86 mounted in annular recesses 87 in the rollback hubs 80 and 81. Thus the rollbacks are permanently and rotatably mounted in the sections of the case and not loosely mounted therein as is the usual custom, so that when the sections of the case are separated to permit reversal of the bolt case, these rollback hubs are not displaced with respect to the associated parts.

In order that the outer knob may be dogged against rotation when desired, the rollback 79 is provided with a slot 90 adapted to receive a lug 91 on the dogging member 31 which is mounted to slide transversely of the case and which may be moved by a fingerpiece 92 at the inside of the door. The dogging slide 31 is releasably held in either of its two adjusted positions by means of the spring-pressed ball 93 mounted therein, this ball engaging one or the other side of the member 26.

When the door is closed, the parts normally stand in the position shown in Fig. 3 in which the dogging lever 55 is normally engaged with the edge of the opening 34 to prevent the retraction of the latch bolt by a tool inserted between the door and the jamb. It will be apparent, however, that when either rollback is rotated in this position resulting in the actuation of the retractor 70, the front portion of this retractor will first act upon the rear beveled edge 95 of the recess 61 to swing the dogging lever 55 in a clockwise direction about the pivot 54 and thus disengage it from the edge of the opening 34. Continued movement of the retractor will cause it to engage the crosshead 45 of the bolt stem and withdraw or retract the latch bolt.

It will be apparent as shown in Fig. 5 that when the portion 12 of the main case is detached, the bolt case 32 may be removed, the bolt stem and dogging lever sliding freely out through the slot 73 of the head 72 of the retractor, and the bolt case then replaced in a reversed position after being rotated through an angle of 180° about its longitudinal axis, thus causing the beveled edge of the bolt head to face in the opposite direction. None of the parts of the mechanism will be disturbed by this operation as even the rollbacks are secured to the respective sections of the case. The operation, therefore, of reversing the latch bolt may be very easily accomplished without any danger of displacing the parts of the lock. It will be noted that during this operation the lock springs are all maintained in their normal positions under tension and there will be no tendency for these springs to fly out as is sometimes the case with locks in use at the present time.

While I have shown and described a preferred embodiment of my invention, it will be understood that it is not to be limited to all of the details shown, but is capable of modification and varia-

tion within the spirit of the invention and within the scope of the claims.

What we claim is:

1. A door lock, a main case of tubular shape having bolt retracting mechanism therein, a cup-shaped bolt case detachably mounted in the forward end of the main case and having an opening in its rear end, the axes of said cases coinciding, a bolt mounted in the bolt case and having a stem projecting through said opening to be engaged by said retracting mechanism, and a dogging lever carried by the stem and also projecting through said opening for engagement by the retracting mechanism.
2. A door lock, a main case of tubular shape having bolt retracting mechanism therein, a cup-shaped bolt case detachably mounted in the forward end of the main case and having an opening in its rear end, the axes of said cases coinciding, a bolt mounted in the bolt case and having a stem projecting through said opening to be engaged by said retracting mechanism, and a dogging lever pivoted to the stem and adapted to engage a part of the bolt case to dog the bolt against retraction.
3. A door lock, a main case of tubular shape having bolt retracting mechanism therein, a cup-shaped bolt case detachably mounted in the forward end of the main case and having an opening in its rear end, the axes of said cases coinciding, a bolt mounted in the bolt case and having a stem projecting through said opening to be engaged by said retracting mechanism, a guard bolt mounted in the bolt case, a dogging lever pivoted to the stem and adapted to engage a part of the bolt case to dog the bolt against retraction, and means carried by said guard bolt engaging the lever whereby the latter is normally held in an inoperative position.
4. A door lock, a main case of tubular shape having bolt retracting mechanism therein, a cup-shaped bolt case detachably mounted in the forward end of the main case and having an opening in its rear end, the axes of said cases coinciding, a bolt mounted in the bolt case and having a stem projecting through said opening to be engaged by said retracting mechanism, a dogging lever carried by the stem and also projecting through said opening for engagement by the retracting mechanism, and spring means acting against the rear wall of the bolt case to urge said bolt to protracted position.
5. A door lock, a main case of tubular shape having bolt retracting mechanism therein, a cup-shaped bolt case detachably mounted in the forward end of the main case and having an opening in its rear end, the axes of said cases coinciding, a bolt mounted in the bolt case and having a stem projecting through said opening to be engaged by said retracting mechanism, a guard bolt mounted in the bolt case, a dogging lever pivoted to the stem and adapted to engage a part of the bolt case to dog the bolt against retraction, a slide mounted on the bolt stem and controlled by said guard bolt, and interengaging means on said slide and lever whereby the latter is normally held in an inoperative position.
6. In a door lock, a main case, a bolt supporting member removably mounted in the forward end of said case, a latch bolt slidably carried by said member having a rearwardly projecting stem, retracting mechanism in the case engaging said stem, and a dogging lever carried by said stem and having a part engaged by said retracting mechanism.

7. In a door lock, a main case, a bolt-supporting member removably mounted in the forward end of said case, a latch bolt slidably carried by said member having a rearwardly projecting stem, retracting mechanism in the case engaging said stem, and a dogging lever carried by said stem and having a part engaged by said retracting mechanism, said supporting member having a part engaged by said dogging lever to dog the bolt against retraction.

8. In a door lock, a main case, a bolt-supporting member removably mounted in the forward end of said case, a latch bolt slidably carried by said member having a rearwardly projecting stem, retracting mechanism in the case engaging said stem, a dogging lever carried by said stem and having a part engaged by said retracting mechanism, and means mounted in the latch bolt and engaging the dogging lever to urge it toward a dogging position.

9. In a door lock, a main case, a bolt-supporting member removably mounted in the forward end of said case, a latch bolt slidably carried by said member having a rearwardly projecting stem, retracting mechanism in the case engaging said stem, a dogging lever carried by said stem and having a part engaged by said retracting mechanism, a guard bolt carried by said supporting member, and a slide controlled by said guard bolt and engaging said lever to urge it to inoperative position.

10. In a door lock, a main case, a bolt-supporting member removably mounted in the forward end of said case, a latch bolt slidably carried by said member having a rearwardly projecting stem, retracting mechanism in the case engaging said stem, a dogging lever carried by said stem and having a part engaged by said retracting mechanism, a guard bolt carried by said supporting member, a slide controlled by said guard bolt and engaging said lever to urge it to inoperative position, and means urging said lever to dogging position when said slide is disengaged therefrom.

11. In a door lock, a main case, a bolt-supporting member removably mounted in the forward end of said case, a latch bolt slidably carried by said member having a rearwardly projecting stem, retracting mechanism in the case engaging said stem, a dogging lever carried by said stem and having a part engaged by said retracting mechanism, said supporting member having a part engaged by said dogging lever to dog the bolt against retraction, said case being of tubular form, and said supporting member, bolt and dogging member being reversible as a unit relatively to said case about the longitudinal axis thereof.

12. In a door lock, a main case, a bolt-supporting member removably mounted in the forward end of said case, a latch bolt slidably carried by said member having a rearwardly projecting stem, retracting mechanism in the case engaging said stem, a dogging lever carried by said stem and having a part engaged by said retracting mechanism, said supporting member having a part engaged by said dogging lever to dog the bolt against retraction, said case being of tubular form, said supporting member, bolt and dogging member being reversible as a unit relatively to said case about the longitudinal axis thereof, and means for securing said supporting member in the case in either of its reversed positions.
